UNITED STATES PATENT OFFICE.

MICHAEL ADAMCZIK, OF KOWNO, LITHUANIA.

LANDING APPARATUS OF AIRCRAFT.

Application filed December 13, 1923. Serial No. 680,554.

To all whom it may concern:

Be it known that I, MICHAEL ADAMCZIK, a citizen of Russia, and residing at Laisves, Al. N. 62, Kowno, Lithuania, have invented 5 certain new and useful Improvements in the Landing Apparatus of Aircraft, of which the following is a specification.

The circumstance that aeroplanes and the like air-craft (hereinafter included in the 10 term "aeroplane") fitted with landing wheels require a comparatively firm and flat surface for taking off from the ground, and more particularly for landing, renders their use difficult in places (such as the wilder roadless districts in the colonies, snow-covered 15 ground and the like) where they would otherwise constitute the best means of transport.

The present invention has for its object 20 to provide an improved apparatus for aeroplanes which is designed to be mounted on the axle journals of the landing framing, in the place of the usual landing wheels, for the purpose of assuring a smooth landing 25 in all circumstances.

The improved apparatus consists mainly 30 of ski-like runners (hereinafter referred to as "ski-runners") suspended in a pendulous manner from the axle journals by means of pendulating arms. These ski-runners are of themselves sufficient for taking off from and landing on to snow-covered ground, but they are also provided with wheels the treads of 35 which project slightly beyond the undersides of the ski-runners. This combination of ski-runners and wheels is of particular advantage for enabling the aeroplane to land upon sandy soil, freshly ploughed fields, stony ground, and ground broken up by 40 ditches and the like, since it not only prevents the aeroplane from sinking into the soil, but also gives to the machine a certain amount of capacity for rolling along the 45 ground.

In contradistinction to the usual use of 50 pneumatic-tyred wheels that are very liable to wear, and are difficult to replace in wild districts, the present invention provides rigid wheels having their axles suspended in a resilient manner relatively to the ski-runners. In view of the length of ski-runners, it is of great advantage to use for each

pair of wheels carried by a lever suspended in a resilient manner symmetrically to the rocking arm. If desired a larger number of 55 wheels may be used, and the several wheels may be connected by a caterpillar or endless track. The entire landing apparatus is preferably enclosed by a cover which extends over the entire length of the ski-runners and thus constitutes a body of least resistance to the air similar to an aeroplane fuselage. 60

With the object of diminishing the air resistance the mechanism that serves for the resilient connection of the landing carriage or frame to the actual landing devices, is 65 also enclosed in the fuselage-shaped cover for the ski-runners. The landing axle which otherwise is movable upwardly in relation to a transverse axle connecting the lower 70 pivotal joints of the landing frame, may be fixed rigidly to the said landing frame, and the said transverse axle may be dispensed with. 75

The landing apparatus further comprises a fixed arm extending downwards from the axle journal against both sides of the free end of which arm the ski-runner casing abuts by means of buffer stops, thus limiting in a resilient manner the extent of the movements of the pendulous arms around the landing axle journal, so that while flying, the ski-runner cover assumes in the air the direction of the aeroplane independently of the latter's changes in speed, whereas on 80 coming into contact with the ground it is able, by yielding longitudinally to adapt 85 itself to the unevenness of the ground to the extent allowed by the buffer mechanism in view of safety in landing. 90

The improvements of this invention are illustrated by way of example in two modifications in the accompanying drawings in which:

Fig. 1 is a longitudinal section of a first 95 modification of the improved landing apparatus taken at right angles to the treads of the ski-runners;

Fig. 2 is a longitudinal section thereof 100 taken parallel to the ski-runner treads; and

Fig. 3 is a cross section taken through the pendulous arms.

Fig. 4 is a section similar to Fig. 1 of a second modification;

Figure 6 is a cross section similar to Fig. 3 of this second modification; and

Figure 5 is a plan of a brake mechanism designed to prevent too great amplitude of movement of the ski-runners.

As shown, 1 is the ski-runner; 2 is the cover; 3 are the pendulous arms for the suspension of the landing apparatus from the axle journals of the landing frame. Next 10 the ski-runner 1 there is fixed to the pendulous arms 3 a stationary axle 4 of steel tubing and, over it, an axle pin 5 is resiliently suspended, movable in slots in the pendulous arms. On this movable axle pin 5 there is mounted a lever 6 which carries the two landing wheels 7, 7¹.

In the second modification shown in Figures 4 and 5, the pendulous arms 3 are not provided with round eyes for their suspension from the landing axle journals, but are slotted, and suspended by means of an extension 9 in a resilient manner from a semi-circular cross bar 8 8' which is situated above the landing axle journal, and serves to secure the two rocking arms 3 firmly together. The axle 4 is fixed to the landing frame and is caused by the impact on landing to move in opposition to the pull of a rubber tension device, in a downward direction in the slots of the pendulous arms 3 so far as the more yielding resilient suspension of the landing wheels 7, 7¹ has not been able to absorb the shock of landing.

35 In the case of a landing axle which is upwardly movable in relation to the pivotal joints of the landing frame, the same effect is produced by suspending with the cross bar 8¹, and fixing the extension 8, above the rubber buffer suspended above the landing axle, to the pivotal joints of the landing frame.

40 Figures 5 and 6 illustrate the construction of the brake which consists of the lever 9 fixed on the landing axle journal. This lever has a slotted lower end, and its slot-prongs embrace a rod 10 fixed to the ski-runner.

45 50 11, 11¹ are buffer springs interposed between the slotted end 9¹ of the lever and the points of attachment of the rod 10.

If desired, the landing apparatus may be 55 suitably enlarged and air chambers or bags be provided in the middle thereof, whereby the landing frame is converted into a pontoon for landing on the water.

What I claim is:—

1. A landing apparatus for air-craft comprising in combination a ski-runner, pendulous arms to which the ski-runner is attached, wheels slightly projecting through the ski-runner, means for resiliently supporting the wheels on the ski-runner, said means being such as to allow a relative movement between the wheels and the ski-runner,

and means on the pendulous arms enabling the whole of the landing apparatus to be pivoted to the axle journal of the aeroplane.

2. A landing apparatus for air-craft comprising in combination a ski-runner, pendulous arms to which the ski-runner is attached, a pair of running wheels, rocking levers carrying the said wheels, means for resiliently supporting the said rocking levers together with the running wheels on the 70 ski-runner, said means being such as to allow a relative movement between the ski-runner and the wheels and rocking levers and means on the pendulous arms enabling the whole of the landing apparatus to be 75 pivoted to the axle journal of the aeroplane.

3. A landing apparatus for air-craft comprising in combination a ski-runner, pendulous arms to which the ski-runner is attached, a pair of running wheels, rocking levers carrying the said wheels, means for resiliently supporting the said rocking levers together with the running wheels on the 80 ski-runner, said means being such as to allow a relative movement between the ski-runner and the wheels and rocking levers and comprising slots provided in the pendulous arms, a fixed pin attached to the pendulous arms, a movable pin capable of sliding 85 in the said slots and on which the rocking levers carrying the running wheels is mounted, and a resilient connection between the fixed and movable pins, and means on the pendulous arms enabling the whole of the landing apparatus to be pivoted to the 90 axle journal of the aeroplane.

4. A landing apparatus as claimed in claim 3, and in which the means on the pendulous arms enabling the whole of the landing apparatus to be pivoted to the axle 100 journal of the aeroplane are such as also to allow a relative movement between the pendulous arms and the axle journal of the aeroplane, in combination with means which 105 are such as to render the said relative movement resilient.

5. A landing apparatus as claimed in claim 1, having a fusiform casing that encloses the pendulous arms, running wheels and the upper portion of the ski-runner, whereby the landing apparatus is caused to have the form of a fuselage corresponding to the main fuselage of the air-craft.

6. A landing apparatus as claimed in claim 1 having a ski-runner casing, a downwardly extending arm fixed to the axle journal of the aeroplane and resilient buffer springs carried by the ski-runner casing for the purpose of limiting the amplitude of the oscillating movement of the ski-runner.

7. A landing apparatus as claimed in claim 1 having a ski-runner casing, a downwardly extended arm fixed to the axle journal of the aeroplane and having a slotted 120

lower end, a rod at right angles to the said arm and the two ends of the said rod which latter ends are attached to the ski-runner-casing, of the arm and the two ends of the said rod which latter ends are attached to the ski-runner-casing,
springs carried by the ski-runner-casing for the purpose of limiting the amplitude of In testimony whereof I have signed my name to this specification.
the oscillating movement of the ski-runner, the said buffer springs being interposed between the two sides of the said slotted end

10

MICHAEL ADAMCZIK.
